CLAIM

[21] Appl. No.: **29/107,026**

The ornamental design for a combined water bottle nipple and cover for child, as shown and described.

[22] Filed: **Jun. 24, 1999**

DESCRIPTION

[51] LOC (7) Cl. **07-01**

FIG. 1 is a front elevational view of the combined water bottle nipple and cover for child of the present invention, the rear elevational view being a mirror image thereof;
FIG. 2 is a left side elevational view of the combined water bottle nipple and cover for child of FIG. 1;
FIG. 3 is a right side elevational view of the combined water bottle nipple and cover for child of FIG. 1;
FIG. 4 is a top plan view of the combined water bottle nipple and cover for child of FIG. 1; and,
FIG. 5 is a bottom plan view of the combined water bottle nipple and cover for child of FIG. 1.

[52] U.S. Cl. **D24/197**
